CLAIM

The ornamental design for a container lid, as shown and described.

DESCRIPTION

FIG. 1 is a top perspective view of a container lid;
 FIG. 2 is a top plan view thereof;
 FIG. 3 is a right side view thereof, the left side view being a mirror image thereof;
 FIG. 4 is a front side view thereof, the back side view being a mirror image thereof;
 FIG. 5 is a cross-sectional view thereof, taken along and in the direction of line 5-5 of FIG. 1; and,
 FIG. 6 is a bottom perspective view thereof.
